UNITED STATES PATENT OFFICE.

WARREN S. GAUNTT, OF KANSAS CITY, MISSOURI, ASSIGNOR TO EARLE H. RORABACK, OF KANSAS CITY, MISSOURI.

COMBINATION CHURN AND FREEZER.

Application filed March 24, 1924. Serial No. 701,370.

To all whom it may concern:

Be it known that I, WARREN S. GAUNTT, a citizen of the United States, residing at Kansas City, in the county of Jackson and 5 State of Missouri, have invented certain new and useful Improvements in Combination Churns and Freezers, of which the following is a specification.

My invention relates to a combination 10 churn and ice-cream freezer and one object is to provide a new and useful apparatus of this character having vibratory supporting means requiring but minimum effort and time in its operation.

15 A further object is the provision of an agitator for use in the churn to break up the butter globules during the churning operation.

Another object is the provision of a lid 20 for centralizing an inner container within an outer container of the apparatus during the process of producing ice-cream.

Other objects will hereinafter appear, and 25 in order that the invention may be fully understood, reference will now be had to the accompanying drawing, in which:

Fig. 1 is a side elevation, partly in section of the apparatus.

Fig. 2 is an irregular horizontal section 30 taken on line II—II of Fig. 1.

Fig. 3 is a plan view of the outer container, the agitator, arranged therein, and the immediate support for said outer container.

35 Fig. 4 is a detail perspective view of the inner container.

Referring now in detail to the various parts, 2 designates an outer container made, preferably, of sheet metal and provided with 40 a handle 4, an upper outlet 6, and a lower outlet 8.

10 designates the inner container also, preferably made of sheet metal and removably arranged within the outer container 2.

45 12 designates a lid for covering the mouths at the upper ends of the containers 2 and 10. Said lid 12 has a depending marginal flange 14 to snugly fit over the upper end of the outer container 2 and has a central circular depression 16 which snugly fits within the upper end of the inner container 10 to hold the same centrally within 50 said outer container 2 as shown by Fig. 1.

An annular rubber or other suitable gasket 55 18, secured inside the lid 12 between its

marginal flange 14 and depression 16, is provided to obtain an air-tight joint between the lid 12 and the upper ends of the outer and inner containers 2 and 10, respectively.

The outer container 2 is provided near its upper end with interior supporting elements 20 which are, preferably, equally spaced apart and arranged to support an agitator 22. Said agitator 22 is, preferably, made from one piece of spring wire formed into a split ring 24 having interior coils 26 and a transverse member 28. The split ring 24 is normally of greater diameter than the interior of the outer container 2 and must be compressed before it can be placed in position upon the supporting elements 20 where it is reliably held until manually removed, by frictional engagement with the inner wall of said outer container 2.

When in use the outer container 2 is supported by a lower transverse bar 30, which in turn is supported by a U-frame 32 formed, preferably, from a single rod threaded at its ends to receive thumb-nuts 34. The U-frame 32 is supported by an upper transverse bar 36, which fits loosely over the threaded ends thereof and is clamped firmly down upon the lid 12 by the thumb-nuts 34.

The upper end of the transverse bar 36 is provided with a centrally-disposed eye 48 in which the lower end of a coil spring 50 is engaged, the upper end of said spring engaging in a supporting member 52 which may be fixed to a vertical wall or other support A. The U-frame 32 is provided with a central bent portion 54 to receive the upper end of a coil spring 56 arranged in alignment with the spring 50 and connected at its lower end to a hook 58, which may be screwed into the floor B.

In practice when butter is to be produced the inner container 10 is removed and the agitator 22 is placed in position upon the supporting elements 20. Stoppers 59 and 60 are placed in the outlets 6 and 8, respectively, after which cream is placed in the container 2, upon which the lid 12 is then placed. The container 2 is then placed upon the lower transverse bar 30, after which the upper transverse bar 36 is placed over the upper ends of the U-frame 32 and down upon the lid 12 where it is firmly held on downward adjustment of the nuts 34. The

5 container 2 is then suddenly forced downwardly to distend the spring 50, which upon rebounding will distend the spring 56. Sudden alternate distension of the springs 50 and 56 imparts a rapid vibratory motion to 10 the churn which in turn agitates the cream and rapidly produces butter, the globules being broken up by violent contact with the agitator 22. After the churning operation has proceeded sufficiently to cause gases to form the stopper 59 is removed for a short time to permit said gases to escape.

15 When ice-cream is to be produced the inner container 10 is substituted for the agitator 22. Cream and its flavoring extracts are then placed within said container 10, while cracked ice is packed in the annular chamber 56 between the cylindrical walls of the outer and inner containers 2 and 10, respectively. While the cracked ice is being placed, the inner container 10 is held centrally within the outer container 2 by a stud 62, which projects upwardly from the bottom of the latter into a protuberance 25 64 in the bottom of the former. The lid 12 is then placed in position to cover the mouths of the inner and outer containers and to coact with the stud 62 and the protuberance in firmly holding the inner container 10 centrally within the outer container 2. The containers are then vibrated to hasten the freezing operation, which is accelerated by the cold air, confined by the lid 12 and gasket 18, being forced around

35 and within the container 10 by the vibratory motion. On completion of the freezing process the salt water can be drained off from the chamber 56, on removal of the stopper 60.

40 From the foregoing description it is apparent that I have produced an apparatus embodying the advantages above pointed out, and while I have shown and described the preferred construction, combination and arrangement of parts, I reserve the right 45 to make such changes as properly fall within the spirit and scope of the invention as claimed.

46 Having thus described my invention, what I claim and desire to secure by Letters Patent is:

50 An apparatus of the character described consisting of a container, a lid thereto, supporting elements spaced about in the interior of said container, and an agitator 55 mounted on said supporting elements and consisting of spring wire formed into an expandible split-ring for frictional engagement with the interior of said container and provided with interior coils, for the purpose described.

56 In testimony whereof I affix my signature, in the presence of two witnesses.

WARREN S. GAUNTT.
